UNITED STATES PATENT OFFICE

JOHN T. GIBBS, OF LONG BEACH, CALIFORNIA

DESIGN FOR A GAME APPARATUS

Application filed August 28, 1931. Serial No. 40,945. Term of patent 3½ years.

To all whom it may concern:

Be it known that I, JOHN T. GIBBS, a citizen of the United States, residing at Long Beach, in the county of Los Angeles and State of California, have invented a new, original, and ornamental Design for a Game Apparatus, of which the following is a specification, reference being had to the accompanying drawings, forming part thereof.

Fig. 1 is a front perspective view of a game apparatus showing my new design; and
Fig. 2 is a fragmentary plan view of the same on an enlarged scale.

I claim:

The ornamental design for a game apparatus, as shown.

JOHN T. GIBBS.
